PRINTING TELEGRAPH APPARATUS

Walter J. Zenner, Des Plaines, Ill., assignor to
Teletype Corporation, Chicago, Ill., a corpora-
tion of Delaware

Application April 22, 1948, Serial No. 22,653

15 Claims. (Cl. 178—25)

1
This invention pertains to printing telegraph apparatus and more particularly to telegraph printers of the page type.

The principal object of the present invention is to provide a printing telegraph apparatus with mechanical refinements of parts to enhance the smoothness and rapidity of operation thereof.

Another object of the invention is the provision in a telegraph printer of novel driving mechanisms therefor resulting in an apparatus capable of exceptionally high speed operation.

A further object of the invention is to provide a page recorder which is exceedingly rapid in operation and very smooth and quiet in performance due to the fact that the rapid movements of the principal parts are provided with controlled acceleration and deceleration to render the mechanism devoid of shocks.

According to the present invention there is provided a novel selecting mechanism of the type disclosed in U. S. Patent No. 2,339,313 issued to W. J. Zenner, but of considerably improved construction and arrangement throughout, of decreased weight and of increased compactness and efficiency, thereby increasing the speed of 25 operation.

Specifically, the telegraph printer according to the present invention comprises a stationary platen, having a type carrier of novel design movable with respect therewith. The type box or carrier slidably supports therein a group of type pallets, the positioning of the type pallet in registry with the printing point being achieved coordinately. The type carrier comprises a rectangularly shaped box having aligned slots or openings in opposite faces thereof to provide dual bearings for the slidable type pallets. Compression springs encircling said pallets within said box hold the pallets in retracted position so that upon receiving a printing stroke from the print hammer, the pallet is actuated to compress its spring and the type face is brought into contact with the record medium.

According to the embodiment of the invention disclosed herein, the type carrier is divided horizontally into four sections, each having four vertical rows of characters. Identifying said sections from left to right as 1, 2, 3, and 4; sections 1 and 2 contain lower case or unshift characters, and sections 3 and 4 contain upper case or shift characters. Thus, the center line between sections 1 and 2 is indicative of the normal position of the type carrier in the unshift or lower case position, so that the type carrier is actuated rightwardly and leftwardly from this

center line for the selection of lower case characters. Similarly, the center line between sections 3 and 4 is indicative of the normal position of the type carrier in the shift or upper case position, so that the type carrier is actuated rightwardly and leftwardly from this center line for the selection of upper case characters.

2
The characters are arranged on the type box or carrier for selection in response to the receipt of code signals in such a manner that characters represented by signals having a marking characteristic for a predetermined impulse (the third impulse) of the five unit code, are on sections 1 and 3 of the type carrier, and characters represented by signals having a spacing characteristic for the said predetermined impulse are on segments 2 and 4 of the type carrier. Signal responsive means is provided which upon the receipt of said predetermined impulse will bias the segment to move in one direction or the other from either of said center lines depending upon the character of said predetermined impulse received. Thus, if the type carrier is in the unshift or lower case position whereat printing from sections 1 and 2 is effected, the reception of a marking characteristic for said predetermined impulse (which in the embodiment disclosed herein is the third interval position of the five unit code) will cause printing to be effected from section 1, and conversely, the reception of a spacing characteristic for said predetermined impulse will cause printing to be effected from section 2. Moreover, if the type carrier is in the shift or upper case position whereat printing is effected from sections 3 and 4, the reception of a marking characteristic for said predetermined impulse will cause printing to be effected from section 3, and the reception of a spacing characteristic for said predetermined impulse will cause printing to be effected from section 4.

The apparatus described generally hereinbefore will, for a five unit code, provide thirty-two selections. However, since there are sixty four possible selective positions on the type carrier, the type carrier may be moved the distance between one of the aforesaid center lines to the other by a case shifting and unshifting mechanism similar in ultimate effect to the case shifting mechanism of the usual form of printing telegraph apparatus. This case shifting mechanism comprises apparatus for shifting the entire type box or carrier from the position to print from sections 1 and 2 to the position to print from sections 3 and 4, or vice versa upon receipt of a shift or unshift signal.

Signal responsive means is also provided for permutatively shifting a series of three stop members for controlling the distance the type box or carrier will move when biased in one direction or the other of the center line. The impulses received in two of the impulse periods (for example, the fourth and fifth intervals of the five unit code) will control the setting of these stops, whereas the impulses received in the other two impulse periods (for example, the first and second intervals of the five unit code) will control the height to which the type carrier is elevated. The type characters on the type carrier are arranged in four horizontal rows. Periodically operated mechanisms are provided for urging the type box or carrier to move rightwardly or leftwardly or to move upwardly at predetermined times in the cycle of operation of the apparatus and said permutatively set means is accordingly provided for interrupting the coordinate movements of the type box or carrier at various right and left positions and different levels.

The foregoing brief description of the features of the present invention apply particularly to the mode of selecting the type to be utilized in printing a character. In accordance with the embodiment of the invention disclosed herein, the type box or carrier is attached to a steel band which is adapted to be wound around a pair of drums disposed one at each end of the printer. The print hammer unit is also attached to a separate steel band which is also adapted to be wound around said pair of drums. The drum disposed at the left end or beginning of line position houses a carriage return spring which is operated according to an old and well known principle. The print hammer assembly or unit operates in a step-by-step manner to impart regular and uniform spacing movement to the print hammer under the control of a pawl and ratchet spacing mechanism, and the idler pulleys around which the steel band is directed are mounted on fixed pivots. On the other hand, the type carrier assembly likewise operates in a uniform step-by-step manner, but the idler pulleys around which the steel band is directed are mounted on a parallelogram device to facilitate variable horizontal shifting movement of the type carrier independently of the uniform character spacing movement to effect type selection. The print hammer is of the firing pin type.

In the embodiment of the invention described herein, it is necessary to perform additional functions such as line feed, carriage return and ribbon feed. The line feed mechanism embodied in the printing apparatus according to the invention differs from the conventional pawl and ratchet line feed mechanism by substituting a gear for the ratchet and a pair of specially designed racks for the usual pawl linkage. The gear is fixed to the platen so as to be rotatable therewith. The racks are adapted to be alternately engageable with the teeth on said gear, with a slight overlap of engageability being provided, so as to impart substantially uniform rotative motion to the gear and platen. Thus, the present line feed mechanism obviates the jerky movement inherent in pawl and ratchet mechanisms and imparts thereto a smoothly accelerated and decelerated motion. The carriage return mechanism is of the usual spring actuated type. The ribbon actuating mechanism is of the type wherein the inking ribbon extends the full length across the platen and is oscillated vertically to give visible

printing. A feature of the invention resides in the provision of clutches individual to the various function mechanisms, such as the type carrier positioning clutch, line feed clutch, function clutch, spacing clutch, code bar actuating clutch and selector clutch.

A more complete understanding of the invention may be had by reference to the following description when considered in conjunction with the accompanying drawings, wherein,

Having reference to Fig. 1 of the drawings, the numeral 11 designates the base portion of the printer framework upon which the apparatus is suitably mounted. In this embodiment of the invention the apparatus is shown as a receiving instrument, and no transmitting apparatus has been shown in connection therewith. It will be understood, however, that suitable transmitting apparatus to which the apparatus of the present invention may respond may be and usually is supplied with an apparatus for receiving messages such as that to be described herein. A suitable transmitting and controlling apparatus is shown in U. S. Patent No. 1,595,472 issued to H. L. Krum, August 10, 1926.

The selector assembly is designated by the reference numeral 12 and comprises a selector magnet 13 (Figs. 1 and 8) suitably supported on a bracket (not shown) attached to the side frame of the printer apparatus. The selector mechanism 12 is essentially of the type shown and described in U. S. Patent No. 2,339,813 issued January 18, 1944, to W. J. Zenner. Extending from the printer side frame is an armature mounting bracket 15 (Fig. 8) which carries, through the instrumentality of a hinge 16, an armature pivot plate 17. To one end of the armature pivot plate 17 is fastened one end of a spring 18, the other end of which is attached to an adjusting screw 19 (Fig. 1) carried in a bracket 21 appropriately mounted on the side frame. The function of spring 18 is to bias the armature pivot plate 17 counterclockwise (as viewed in Fig. 8) about the hinge 16 in response to a spacing condition impressed on the selector magnet 13. In response to a marking signal condition the magnet 13 becomes energized and armature 17 is attracted toward the pole piece 22, thereby stretching the spring 18. The armature plate 17 thus oscillates in response to received code combinations of marking and spacing impulses.

Cooperating with the leftward extremity (as viewed in Fig. 8) of armature plate 17 are a plurality (five in the present embodiment) of selector levers 23 pivotally mounted on a pivot shaft 24. Each of the selector levers 23 is provided with a cam follower projection 25 and is adapted to cooperate with a selector cam 26 individual thereto. Cams 26 are fixed to a shaft 27 to which rotation is imparted by means of a motor 28 (Fig. 1). Selector levers 23 are normally biased toward cams 26 by individual springs 29 in such a manner that the projection 25 normally bears against the outer periphery or dwell portion of the cam 26 and in this position the upper extremity of each lever 23 cooperates with the edge of the armature plate 17. Associated with each lever 23 and operably disposed thereabove is an interponent 31 pivotally mounted on a pivot shaft 32 suitably journaled in the printer frame. Interponents 31 are normally biased in a clockwise direction (as viewed in Fig. 8) by their individual springs 33 so that the extremity of each interponent 31 normally rests upon the upper end of its associated lever 23. In the present embodiment, the interponents 31 are each provided with an open-ended slot 38 in order that the interponents 31 are slidable on the pivot shaft 32.

Cooperatively related to interponents 31 are a corresponding series of substantially T-shaped members 34. The rounded extremity of the horizontal arm of the member 34 cooperates with interponent 31 and normally bears thereagainst under the influence of individual springs 35. The upwardly directed arm of each member 34 is pivotally articulated to the horizontal arm of an associated bell crank lever 36 pivotally mounted on a shaft 37. The vertical arm of bell crank lever 36 is likewise pivotally articulated to associated code bars 62 to 70. Cooperating with said code bars are a plurality of selectable bars 39 for controlling the various functions of the apparatus, as will be hereinafter described.

The depending arm of each T-shaped member 34 is provided with shoulders 41 and 42 which are adapted to coact selectively with a pair of reciprocably operating bail members 43 and 44, respectively. Bail member 43 is provided with stepped shoulders 45 to correspond to the echelon arrangement of members 34 and the horizontal arms of bell cranks 36, which shoulders 45 co-operate with the shoulders 41. Similarly, bail member 44 is also provided with stepped shoulders 46 to coact with the shoulders 42.

Bail members 43 and 44 are mounted for vertical sliding movement on frame portion 47, and each is provided at its lower end with open-ended slots 48 and 49, respectively, adapted to receive the circularly conformed ends 51 and 52 of an oscillating drive member 53 fixed to a shaft 54 appropriately journaled in the frame of the apparatus. At the opposite end of shaft 54 (as shown in Fig. 10) is fixed an arm 55, and juxtaposed to arm 55 and freely mounted on shaft 54 is an arm 56. Fixedly carried on arm 56 is a stud 57 which is adapted to bear against a shoulder 58 on arm 55 due to the pull of a spring 59 which is stretched between the extremities of the arms 55 and 56. Also connected pivotally to arm 56 through the medium of stud 57 is an eccentric link 61 cooperatively related to an eccentric 60 fixed on the main operating shaft 27 of the printer apparatus.

Associated with the armature lever 17 is a clutch trip lever 71 (Figs. 8, 9 and 29) which is pivotally supported on a pivot stud 72 and is normally biased clockwise by a spring 73 against the edge of the armature 17. A plurality of cams including the selector cams 26 are mounted on the operating shaft 27 on which is also mounted a clutch mechanism 111 represented in Fig. 9 by its stop lever 74. The clutch mechanism thus indicated 111 is of the type disclosed in copending application Serial No. 707,176 filed November 1, 1946, by A. N. Nilson et al., and lever 74 is analogous to lever 27 of said application.

A bell crank lever 75 is pivotally mounted at pivot 76 on an orientation plate 77 of well known construction; for example, comparable to the plate 75 shown in Fig. 9 of U. S. Patent No. 1,989,710 issued to A. H. Reiber et al. The rotation of plate 77 is effected through the instrumentality of rack and pinion means, exemplified by thumb screw 80 in Fig. 29, and is similar to that shown in Fig. 9 of said copending Nilson et al. application. Arm 78 of the bell crank lever 75 is adapted to cooperate with the clutch lever 74, and the other arm 79 of said lever 75 is provided at its extremity with a pair of studs 81 and 82 suitably spaced to guide the lever 71 so that as the lever 71 is actuated by the spring 73, this actuation would be imparted through

the studs 81 and 82 to the bell crank lever 75, as will hereinafter appear. The contour of the lever 71 adjacent the studs 81 and 82 is such that the vertical position of the lever 71 will not be disturbed when the orientation adjustment of plate 77 is being made. A cam 83 is secured to the shaft 27 in a position to cooperate with the stud 82 of bell crank lever 75. Cam 83 in its stop or rest position presents the notched portion thereof to the stud 82 as shown in Fig. 9.

Referring to Figs. 8 to 11, a description of the operation of the mechanism so far described will now be given. The selector cam assembly carried on shaft 27 is rotated at a speed substantially equivalent to the speed of code pulsing, and operating in conjunction therewith is the selector magnet 13 which may be connected either directly or indirectly to the signal line (not shown). In accordance with well known practice, the normal stop condition of the line is marking, hence the selector magnet 13 is normally energized and its armature 17 is held attracted to present the end thereof into the path of the trip lever 71. During the first line impulse or start interval which is of spacing nature, the selector magnet 13 is de-energized and the spring 18 retracts the armature 17 to the dotted position 84 as shown in Fig. 9 to permit spring 73 to rotate the lever 71 clockwise, which, through studs 81 and 82 rotates bell crank lever 75 similarly to disengage the end of arm 78 from the clutch lever 74. This action is permitted because the notch 85 of cam 83 is opposite stud 82. The clutch 111, exemplified by lever 74, thereupon is permitted to rotate to, in turn, impart rotation to the selector cam assembly. At the termination of the start interval, the cam 83 upon rotation will act to cam the bell crank lever 75 counterclockwise to hold the end of arm 78 in the path of clutch lever 74. Studs 81 and 82 will also hold the lever 71 free of the armature 17 thereby imposing no load upon said armature. Lever 71, therefore, cannot respond to the pull of spring 73 until the notch 85 is again presented in register with stud 82.

During the ensuing rotation of the selector cam assembly, the selector cams 26 will control the selection of levers 23. Each of the levers 23 (five in the present embodiment) is provided with a cam follower projection 25, as previously described, which cooperates with the periphery of its associated cam 26. The cams 26 are of similar cam contour but are displaced on the shaft 27 angularly so that the cam projections thereon are disposed in a helically arranged series whereby coaction with the cam followers 25 will occur in a sequential manner as the series of cams 26 rotates in synchronism with the speed of code impulsion.

As the selector cams 26 rotate, the notch or depression 86 of the first cam 26 is presented to the cam follower projection 25 during the first signal impulse of the received code combination. If said impulse is of marking nature the armature 17 will assume its attracted position and the first lever 23 will be free to respond to the pull of its spring 29. Lever 23 will then be withdrawn from beneath the end of slide or interponent 31 which under the influence of its spring 33 will rotate slightly to rest upon the flange 87 of reset bail 88 pivotally mounted at pivots 89 on frame member 91. As the selector cam 26 continues to rotate, the high portion 92 thereof will coact with the cam projection 25 to rotate lever 23 in a counterclockwise direction, where-

upon the slide or interponent 31 will be urged leftwardly to cause T-member 34 to rotate slightly about pivotal interconnection 33 to bring shoulder 41 of member 34 beneath the bail blade 45 which on its downward movement will draw member 34 downwardly to in turn impart counterclockwise rotation to bell crank lever 36 to cause the associated code bar 62 to be shifted leftwardly (as viewed in Fig. 8).

If the first significant code impulse had been a spacing impulse, the magnet 13 would have been de-energized, and the armature 17 would have been released to block the clockwise movement of lever 23 (Fig. 9) as previously described, whereupon the extremity of interponent 31 will continue to ride on top of lever 23 and no leftward slidable movement of interponent 31 will occur. T-member 34 will remain in the position shown in Fig. 8, so that the shoulder 41 thereof will be presented in the path of the reciprocating bail 44 to cause upward movement of member 34 to in turn rotate bell crank 36 clockwise to impart rightward movement to code bar 62.

A locking lever 94 is normally spring biased toward the armature 17 to retain the armature in its released or attracted position during the signal impulse interval. The function and operation of this lever is fully disclosed in U. S. Patent No. 1,783,382 granted to H. L. Krum. Following the selective operation of the selector levers 23, as previously described, the reset bail 88 is operated by its cam 95 to raise the interponents, which have previously been dropped, to restore the interponents to the position shown in Fig. 8.

The code bars 62 to 70 extend across the printer and control the selection of functions, such as line feed, carriage return, shift and unshift, and also the selection of type characters for printing, as will be hereinafter described. As shown in Fig. 22, the code bars 62 to 70 are suitably supported for movement in the direction of their length by brackets 20 and 30 secured to plate 253.

Having reference to Fig. 29, a driving pinion 101 secured to the shaft 102 driven by the motor 28, serves to transmit power through a gear 103 to the main operating shaft 27 of the printer. On shaft 27 are carried a plurality of clutches for governing the various functions of the apparatus. The clutch indicated generally as 105 controls the power for elevating the type box or type carrier 99 (Figs. 1 and 44). Clutch 106 controls the power for operating the line feed mechanism. Clutch 107 is the function lever clutch, and acts, as will hereinafter appear, to control a function lever bail 367 (Fig. 15). Clutch 108 is the spacing clutch and controls the power for operating the stepping of the printing mechanism. Clutch 109 is the code bar operating clutch and controls the oscillation of drive member 53, shown in Figs. 8 and 10. The clutch indicated generally as 111 controls the power for operating the selector cams.

Clutches 105 to 109 are of the construction illustrated in Figs. 31 and 32. The particular clutch shown is clutch 106 of Fig. 29 which controls the line feed mechanism. Having reference to Figs. 31 and 32, a ratchet wheel 112 constantly rotates with the constantly rotating shaft 27 and constitutes the driving portion of the clutch. The driven portion comprises a pair of pawls 113 and 114 pivotally mounted on a flange 115 of a sleeve member 116 loosely carried on the shaft 27. Pawls 113 and 114 are normally

biased clockwise by individual springs 117 distended between the end of the pawls and associated spring posts 118 mounted on the flange 115. One pawl, or even three or more pawls may, of course, be used. Integral with the sleeve 116 is flange 119 provided with diametrically disposed studs 121 and 122 carrying rollers 123 and 124 which cooperate with an accelerator lever 129, as will presently be described.

The clutch 106 is shown in Fig. 32 in its stop condition of operation with the stop portion 126 of flange 115 bearing against the extremity of its associated stop gate 127, shown more clearly in Fig. 15. However, just prior to the engagement of stop lug or portion 126 with stop gate 127, during a cycle of rotation of the clutch, the pawls 113 and 114 have become disengaged from the ratchet wheel 112 due to the coaction of the tail portion of each pawl with its associated deflector 128 which is a fixed part of the machine.

Rollers 123 and 124 are adapted to cooperate with accelerator arm 129 pivoted on a stud 131 fixed to a bracket 132 suitably carried on a pair of cross bars 133 (one of which is shown in Fig. 29). An accelerator spring 134 normally biases arm 129 in a counterclockwise direction (as viewed in Fig. 32) against one or the other of the rollers 123 or 124 (depending upon the position of the clutch) to tend to rotate the sleeve 116 clockwise (as viewed in Fig. 32) which clockwise rotation is prevented by the portion 126 bearing against the gate 127.

When the extremity of gate 127 is removed from the path of portion 126 (in a manner hereinafter described), the driven portion of the clutch is released for rotation. However, the pawls 113 and 114 are prevented by deflectors 128 from engaging the ratchet 112 at this time. This is done purposely in order to prevent a clashing of the rapidly moving ratchet teeth with the quiescent pawl teeth. Thus the function of the accelerator 129 becomes apparent. As soon as the stop gate 127 is disengaged from portion 126, the accelerator arm 129, due to the energy stored in spring 134, suddenly imparts clockwise rotation to sleeve 116 to in turn impart a rapid forward movement to pawls 113 and 114. Thus, pawls 113 and 114 are thrown free of the fixed deflector members 128 and are brought into engagement with the ratchet wheel 112 by their associated springs 117. In this manner, momentum is imparted to the pawls 113 and 114 before their engagement is effected with the rapidly rotating ratchet wheel 112, thereby preventing the breaking of the ratchet teeth or the pawl teeth. As the clutch driven member or sleeve 116 is completing its rotation, energy is again stored in the accelerator spring 134 by the coaction of rollers 123 or 124 with the cam surface 135 of the accelerator arm 129. Then, as the sleeve 116 completes its rotation, the tail portions of the pawls 113 and 114 again cooperate with the fixed deflector members 128 to effect the disengagement of the pawls 113 and 114 from the ratchet 112.

Clutches 105, 107, 108, and 109 are of similar construction to clutch 106. However, these various clutches are initiated into rotation under the control of the mechanism schematically shown in Fig. 30. Having reference to Fig. 29, the armature 17, in response to a spacing signal, releases lever 71, which, through studs 81-82, coacts with arm 79 of release lever 75 to rotate said lever 75 to release arm 78 from clutch 111 to thereby initiate rotation of the selector cam assembly 136. The selector cam assembly includes a cam

suitably shaped to actuate, at a predetermined time in the rotation of the assembly, a trip lever 137 fixed to a shaft 138 suitably supported in the apparatus. To the other end of shaft 138 is fixed a stop gate 139 (similar to stop gate 127) which coacts with a stop portion in clutch assembly 109 which is similar to portion 126 in clutch 106. Associated with clutch assembly 109 is a cam which cooperates with a trip lever 141 fixed to a shaft 142 appropriately mounted in the apparatus. Also fixed to shaft 142 are stop gates 143 and 144, for initiating operation of clutches 107 and 105, respectively, since in the embodiment of the invention shown the clutches 105 and 107 are operated substantially simultaneously. Included in the clutch assembly 105 is a trip-off cam which operates a trip lever 145 fixed to a shaft 146 to the other end of which is fixed a gate 147 for initiating operation of the clutch 108.

Thus, in the cycle of operations the selector cam assembly 136 (Fig. 29) is initiated into rotation upon the receipt of the start impulse, and at a predetermined time in its rotation a cam 149 thereon actuates the lever 137 to rock the shaft 138 to thereby operate stop gate 139 to initiate the rotation of clutch 109 to effect the operation of the code bars and function levers. A cam 151 in the clutch assembly 109 in turn actuates the arm 141 at a predetermined time to rock the shaft 142 to operate the stop gate 144 to initiate the rotation of the clutch 105 to effect the operation of the type box 99. A cam 152 in the clutch assembly 105 actuates, at a predetermined time, the lever arm 145 to rock the shaft 146 to operate the stop gate 147 to initiate operation of the spacing clutch 108. The selector cam assembly 136 is also provided with the cam 83 which cooperates with the U-shaped lever 75, for the purpose aforesaid.

Having reference to Figs. 1, 2, 6, and 44 to 46, the type carrier 99 comprises a hollow box-like structure having aligned apertures in the front and rear faces thereof into which are slidably supported the type elements 155. A coiled compression spring 156 having one end secured to the shank of the type element encircles each type element 155 and functions to hold the type element in the retracted position (as shown in Fig. 46). The type carrier 99 is provided with flanges 157 through the medium of which the carrier 99 is mounted on a traveling carriage 158 by means of screws 159. In the present embodiment, the carriage 158 is provided with a pair of upper rollers 161 and a lower roller 162 adapted to ride on the upper and lower edges of a track member 163 (Figs. 6 and 13).

Track 163 is secured near each end by means of bolts 164 to the upper ends 160 of correspondingly conformed members 165 and 166 (Figs. 13 and 18, respectively). Members 165 and 166 are corresponding elements of corresponding parallel motion arrangements located on each side or end of the apparatus, as shown in Figs. 13 and 18. Referring to Fig. 13, the member 165 is pivotally articulated at pivot 167 to the free end of a lever arm 168 pivotally mounted on a stud 169 fixed to the side plate 171 of the apparatus. The lower end of member 165 is pivotally connected through pivot 172 to the free end of a lever arm 173 pivotally connected at 174 to the side frame 171. Lever 173 is provided at its extremity with a projection 170 adapted to slide vertically in a guide-way 180. Movement vertically is imparted to the members 165 and 166 in the following manner. The clutch 105 is indicated in broken lines in

11

Fig. 13, but at the predetermined time in the cycle of operations of the apparatus, the gate 144 (Fig. 30) therefore is actuated to release the clutch 105 for a full revolution, the clutch 105 being provided with only one pawl 114.

Associated with the clutch 105 is a disc 174 which is provided eccentrically thereon with a stud 175 to which is pivotally connected one end of a link 176, the other end of which is connected pivotally to the end of a lever arm 177 fixed to a rock shaft 178 suitably journaled in the apparatus. Also fixed to shaft 178 is an arm 179 to the free end of which is pivotally connected the lower end of a vertical link 181. The upper end of link 181 is pivotally connected to a lever arm 182 which is pivotally supported at 183 to the side frame or plate 171. A connecting link 184 is connected pivotally at 185 to the lever arm 182. The upper end of link 184 is pivotally connected to arm 187 of the lever 168 which is pivotally supported at 169 on the side plate 171. Arm 187 is provided with a depending projection 188 to the extremity of which is pivotally articulated one end of a link 191, the other end of which is pivotally connected to a ribbon spool platform 192 rockably mounted on the side plate 171 by means of pivot stud 193. Fastened to side plate 171 is a guide comb 194 which is suitably slotted for guiding the movement of levers 173 and 182.

A link 195 comprising one element of a toggle or knee-action device is pivotally connected at 196 to the extremity of lever arm 182. The other element of the toggle comprises the link 197 which is pivotally connected at 198 to the member 165 and at 190 to the other element or link 195. The toggle or knee-action device illustrated is of the type disclosed in co-pending application Serial No. 656,284 filed March 22, 1946, by W. J. Zenner. Toggle element 197 is provided with an anticipator or buffer portion 199 adapted to cooperate with a selected one of the selectable code bars 63, 65, 67, and 70. Toggle element 197 is normally urged in a counterclockwise direction by a spring 201 distended between a spring post on the element 197 and a spring post on the member 165. Toggle element 197 is also provided with a projection 202 which cooperates with a lateral projection 203 of member 165 to limit the counterclockwise movement or rotation of the toggle element 197 by the spring 201. Thus, the toggle device is shown in Fig. 13 in its quiescent condition with the projection 202 resting against the stop 203.

The structure just described in Fig. 13 is employed for governing the vertical selective movement of the type box 99. In Fig. 18 is shown a corresponding structure which in conjunction with the structure shown in Fig. 13 serves to raise the track 163 to in turn raise the type box 99. Thus, having reference to Fig. 18, an arm 204 is fixed to the shaft 178, and a link 205 connects the arm 204 to a lever 206 corresponding to lever 182. Lever 206 is connected by a link 207 to a lever 208 corresponding to the lever 168. Lever 208 is connected at its free end to the upper end of member 166, while the lower end of member 166 is connected to a lever 209 similar to lever 173. Levers 208 and 209 are connected to the member 166 in a parallel-motion manner, identical with the manner in which levers 168 and 173 are connected to the member 166.

A toggle or knee-action device comprising elements 211 and 212, and spring 213 is also provided between lever 206 and member 166. Elements 211 and 212 are pivotally articulated at

75

12

210. Element 212 is provided with an anticipator portion 214 which also cooperates with the stop bars 63, 65, 67 and 70, and together with the corresponding structure shown in Fig. 13 an arrangement is thus provided for elevating the track 163. Element 212 is also provided with a projection 215 which cooperates with a lateral projection 216 on member 166. Lever 208, through projection 217, operates a link 218 which, in turn, actuates a ribbon spool platform or support 219 corresponding to support 192.

In the operation of the type box elevating mechanism shown in Figs. 13 and 18, the bars 63, 65, and 67 are selectively projected into the path of anticipators 199 and 214 and stop shoulders or abutments 221 and 222 of members 165 and 166, respectively, through the instrumentality of the selector arrangement shown in Fig. 8. For example, in response to a marking condition the member 34 (Fig. 8) will be actuated to its leftward position to place its shoulder 41 in the path of the bail 43 to thereby rotate bell crank 36 counterclockwise, thus moving bar 63 or 65 leftwardly (as viewed in Fig. 8, or rightwardly as viewed in Fig. 20). There are bell cranks 36 associated with bars 63 and 65 and not with bar 67. Of course, there are bell cranks 36 associated also with bars 62, 64 and 66 for a purpose to be hereinafter described.

As clearly shown in Fig. 18, bar 67 is provided with a vertically directed arm 223 adapted to cooperate with a shoulder 224 (Fig. 20) on bar 63 and a corresponding shoulder on bar 65. Bar 67 is normally spring-biased rightwardly by a spring 229, as viewed in Fig. 20, so that it is permitted to move to the right only upon the selective operation rightwardly (as viewed in Fig. 20) of both bars 63 and 65. Having reference to Fig. 6 it will be noted that the type carrier 99 is provided with four horizontal rows of type faces, and to effect printing in said rows, the type carrier 99 is elevated to any one of said four positions. These positions are governed by the stop bars 63, 65, 67, and 70. The bar 70 is fixed in its position and determines the highest position to which the carrier 99 is moved, whereat printing will be effected from row 225. When printing is to be effected from row 226 the bar 63 is selected and is actuated rightwardly (as viewed in Fig. 20) to limit the upward movement of anticipators 197 and 214, and shoulders 221 and 222. Under this condition of operation the bar 67 is held against movement by the shoulder 224 on bar 65, and on the other hand, when the bar 65 is selectively actuated rightwardly to position the carrier 99 for printing from row 227, the shoulder 224 on bar 63 will hold bar 67 against movement. However, when printing is desired from row 228, both bars 63 and 65 are selectively actuated rightwardly, thereby removing the block from projection or arm 223 to permit bar 67 to move rightwardly. When neither bar 63 nor bar 65 is selected, then the anticipators are permitted to abut bar 70 to effect printing from row 225, as indicated above.

The selection of bars 63, 65 and 67, through the instrumentality of the selector cam assembly 136 and the code bar operating mechanism shown in Fig. 10, causes a cam associated with the code bar operating mechanism to operate an arm 141 (as previously described) to rock the shaft 142 (Fig. 30), which through arm 144 will initiate the rotation of the type carrier clutch 105. As viewed in Fig. 13, the clutch 105 governs the rotation of the disc 174 which, in turn, through link 176, con-

trols the oscillation of arm 177 to rock the shaft 178 on which are fixed the arm 179 (Fig. 13) and the arm 204 (Fig. 18).

Arms 179 and 204 actuate their respective links 181 and 205 to operate their respective lever arms 182 and 206 to control the operation of their respective knee-action mechanisms. Since the free ends of levers 182 and 206 are connected to the lower extremities of their respective knee-action mechanisms, and stop members 165 and 166 are connected to the upper extremities thereof, the elevation of the members 165 and 166, and therefore the track 163, is accomplished through the knee-action mechanisms until a stop bar 63, 65, 67, or 70 has been encountered, whereupon the knee-action joints bend at their pivots 190 and 210, as described in the afore-mentioned copending application, Serial No. 656,284.

As set forth in said copending application, the buffer portions or anticipators 199 and 214, in their upward movement are the first to strike a stop bar 63, 65, 67, or 70 which has been projected into their path of movement, and in response to further movement imparted to levers 182 and 206 by the shaft 178 through links 181 and 205, respectively, the knee-action elements 197 and 212, due to the knee-action, tend to rotate about pivots 198 and 200, thereby stretching their respective springs 201 and 213, until the striking edges of the anticipators 199 and 214 and of the stop shoulders 221 and 222 coincide, and said shoulders 221 and 222 thus are brought to bear against the selected stop bar. Thus, said knee-action elements provide a yielding or cushioning means for the movable members 165 and 166.

It is observed that the movement imparted to levers 182 and 206 is fixed and invariable, while the movement imparted to members 165 and 166 is variable and is governed by the stop bars 63, 65, 67, and 70. The utility of the knee-action drive resides in the provision of a compensating means for these two different types of movement. Furthermore, the shock due to the moving object or members 165 and 166 striking against the fixed stops 63, 65, 67 or 70 is dissipated, and as the members 165 and 166 approach the stops 63, 65, 67, or 70 at high speed, the impingement of stop projections or shoulders 221 and 222 upon the stop bars 63, 65, 67, or 70 is anticipated by the anticipator or buffer portions 199 and 214, so that a gradual slowing down of the movement of members 165 and 166 occurs, whereby the members 165 and 166 are caused to come to rest lightly against the selected stop bars 63, 65, 67, or 70. Moreover, as the stop projections 221 and 222 recede from the stop bars, the movements thereof are likewise governed by the knee-action means, whereby the acceleration of motion of members 165 and 166 corresponds inversely to the deceleration, so that the members 165 and 166 start from rest and gradually accelerate until the motion of link 205 (or 182) is attained.

Also pivotally connected to the extremity of lever 182 is a detent or check member 231 provided with a guiding projection 232 adapted to cooperate with a guide comb 233. As the member 231 is raised by lever 182, a cam portion 234 (Fig. 17) of projection 232 cooperates with a cam surface 235 on a guide member 236 to direct a check pawl tooth 237 into one of the notches 238 on member 165. A detent member 241, corresponding to member 231, is also pivotally connected to lever 206 (Fig. 18) and is provided with a projection or extension 242 having a cam por-

tion cooperating with a guide 243 to cam a pawl tooth 244 into engagement with one of the notches 245 in the member 166. The vertical movement of member 231 is always the same, while the vertical movement of member 165 varies according to the stop member 63, 65, 67, or 70 selected. Accordingly, the pawl tooth 237 will be cammed forward at the same point, but since the movement of member 165 varies, the pawl 237 will engage the notch 238 in register therewith as determined by the stop bars. Corresponding cooperation will result between pawl 244 and notches 245 (Fig. 18).

The mechanism for elevating the type box to any one of four horizontal rows has now been described. However, to bring the type pallets in these horizontal rows into registry with the printing point, the following described mechanism is employed. Having reference to Figs. 8 and 15, it was disclosed that code bars 63, 65, and 67 determine the elevation of the type box or carrier 99 to control printing from the different horizontal rows 225, 226, 227, or 228. The code bars 62, 64, and 66, however, determine the degree of horizontal movement of the type carrier to complete the selection of a particular type face in a particular row. Referring to Fig. 8, the code bars 62, 64, and 66 are also actuated rightwardly or leftwardly by their associated bell cranks 36 in the same manner as previously described in connection with code bars 63 and 65. As shown in Fig. 3, the code bars 62 and 64 are notched at 246 to receive the ends of one arm of small bell crank levers 248 and 249 pivotally mounted on a pivot 251 carried in a bracket 252 secured to the front plate 253 of the printer. The extremities of the other arms of the bell cranks 248 and 249 engage notches in slidable stop elements 254 and 255, respectively, appropriately mounted on a bracket 257 secured to plate 253.

Interposed between stop elements 254 and 255 and controlled thereby is a third slidable stop element 256. As viewed in Fig. 3, stop element 256 is normally biased rearwardly by a spring 258 stretched between said stop element and the plate 253. Stop elements 254, 255 and 256 are each provided with a pair of oppositely directed stop projections 259 and 261. The projections 259 and 261 of each stop element differ in length from the corresponding projections of the other two stop elements in such a manner that the type carrier 99, as will presently appear, will be brought into registry with the different vertical rows of type pallets 155 depending upon which of the stop elements 254, 255, and/or 256 have been actuated.

Cooperating with the stop projections 259 and 261 is a buffer member 262 provided with buffer portions 263 interposed between the stop projections 259 and 261 and associated knee-action mechanisms of the type disclosed in the afore-mentioned copending application Serial No. 656,284. Buffer member 262 is slidably mounted on a plate 264 by means of slot and screw mounting means 265.

When spacing impulses are received in the fourth and fifth intervals of the code, the code bars 62 and 64 remain in the positions shown in Fig. 3, and accordingly, the projections 259 and buffer portion 263 will be in alignment as shown, whereby the longest projections, which are on the middle stop element 256, are effective. When a marking impulse is received in the fourth interval and a spacing impulse is received in the fifth interval, only code bar 62 will be actuated

(rightwardly, as viewed in Fig. 3), whereupon stop element 254 will be moved outwardly (downwardly as viewed in Fig. 3). Element 254 in so moving engages a vertically extending projection 266 (Fig. 5) on the middle stop element 256 so that element 256 thus is carried along with the element 254, thereby exposing projections 259 and 261 on stop element 255 to the buffer portions 263.

When a spacing impulse is received in the fourth interval and a marking impulse is received in the fifth impulse interval, only code bar 64 will be actuated whereupon stop element 255 will be moved outwardly. Stop element 255 in so moving engages a downwardly directed projection 267 on the middle stop element 256 so that, in this case also, stop element 256 thus is carried along with the element 254 thereby exposing projections 259 and 261 on stop element 254 to the buffer portions 263. Lastly, when marking impulses are received in both the fourth and fifth impulse intervals, the code bars 62 and 64 will both be actuated outwardly, whereupon the middle stop element 256 will also be similarly actuated and therefore all the projections 259 and 261 will be moved out of the path of the buffer portions 263 which will therefore be permitted to move the maximum distance until one or the other of the buffer portions 263 will abut one of the surfaces 268 of the stop elements.

Plate 264 is slidably guided in comb brackets 268 and 269 (Fig. 2) secured to the front plate 253, which brackets also guide the member 271, more fully shown in Fig. 6. Plate 264 is provided with pivot studs 272 and 273 secured thereto, on which are mounted pivotally a pair of links 274 and 275, respectively, of the afore-mentioned knee-action mechanisms. Link 274 is normally biased counterclockwise by a spring 276 stretched between a spring post 277 on link 274 and a spring post 278 on the plate 264. Similarly, link 275 is normally biased clockwise by a spring 279. Pivotally articulated to link 274 at 281 is a link 282, the other end of which is connected pivotally to a lever arm 283, which is pivotally mounted on a pivot stud 284 secured to the front plate 253. Links 274 and 275 are provided with anticipators or buffer portions 285 and 286, respectively, such as described in copending application Serial No. 656,284. A link 287 similar to link 282 is pivotally connected to the link 275 and to an operating lever arm 288, analogous to arm 283, mounted pivotally on a pivot stud 289 secured to the front plate 253. Links 282 and 287 are provided with laterally directed flanges 291 to limit the rotational movement of the toggle links. Links 282 and 287 are also provided with cam portions 280 and 290, respectively, for a purpose to be described.

Mounted on the pivot connecting the link 287 and the lever arm 288 is a swivel member 292 having a pair of arms for slidably supporting a member 293. Integral with member 293 is a slotted portion 294 adapted to cooperate with a stud 295 extending from one end of a rocker member 296 pivotally mounted at 297 to the bracket 257. Member 293 is also provided with a shoulder portion 298 which cooperates with a flange 299 on plate 264, as will hereinafter appear. A compression spring 301 is disposed around the bar 293 between the swivel 292 and the shoulder 298. A member 302, similar to member 293, is slidably carried in a swivel member 303 pivotally connected to the pivot 304 between arm 283 and link 282. Member 302 is also pro-

vided with a shoulder portion 305 and slotted portion 306, and is surrounded by a compression spring 307. Cotter pins 308 retain the members 293 and 302 with respect to the swivels 292 and 303. Cooperating with the slotted portion 306 is a stud 309 secured to rocker member 296.

Referring to Fig. 6 it is observed that studs 295 and 309 on rocker member 296 cooperate with cam projections 311 and 312, respectively, de-

10 pending from the member 271 so that, as the member 271 is actuated rightwardly and leftwardly, in a manner to be described, the rocker member 296 will be rocked counterclockwise and clockwise, respectively. Member 271 is also provided with laterally directed projections 313 and 314 which cooperate with the cam portions 280 and 290 of links 287 and 282, respectively. Member 271 is provided at its right end (as viewed in Fig. 6) with a notch 315 adapted to receive one end of a lever 316 (Fig. 4) pivotally carried at 310 on the bracket 268. The other end of the lever 316 is articulated to the direction code bar 66 through the instrumentality of a notch in a flange 317 on the code bar 66.

20 Plate 264 has also affixed thereto pivot studs 318 and 319 to which links 321 and 322, respectively, of a pair of toggle devices are pivotally connected (Figs. 2 and 6). Links 321 and 322 have connected thereto at pivots 323 and 324, links 325 and 326, respectively. The opposite ends of links 325 and 326 are connected by pivots 327 and 328 to brackets 329 and 331, respectively, which are secured to a channel member 332 (Figs. 2, 6, and 7). The channel member 332, 30 through extensions of its flanges 333 is supported pivotally on pivot shaft 334 carried by members 335 pivotally mounted at 330 to brackets 337 secured to the front plate 253. Only the support 335 at one end of the channel member 332 is shown 40 in Fig. 6. However, in Fig. 1 both supports 335 are illustrated.

Asride the inverted U-shaped member 322 is a saddle member 336 (Figs. 6 and 7) for controlling the movement of the type carrier 99. A flexible metal strap 337 is clamped between the top of the saddle member 336 and a clamping plate 338 and secured by screws 339. Saddle member 336 is provided with a pair of integral studs 341 and 342 on which are pivotally supported a pair of links 343 and 344 which are rigidly connected together for movement as a unit by means of a thimble or separator 345 and a bolt 346. Link 344 is connected pivotally to the main portion of carriage 158, and link 343 is pivotally connected to an arm 347 integral with and extending from carriage 158. Thus, it is seen that with the interconnection just described, the type carriage 158 can be elevated by the mechanism shown in Figs. 13 and 18, simultaneously 60 with movement horizontally, now to be described.

As viewed in Fig. 5, there is also clamped to shaft 178 an arm 348 which is oscillated as the shaft is rocked by the arm 177 and link 176 through the instrumentality of clutch 105 (Fig. 13). Pivotally articulated to the end of arm 348 is a lever 349 which is fixed to a shaft 289 (Fig. 2) suitably journaled in the frame of the printer. Also fixed to shaft 289 is an arm 351, to the free end of which is pivotally connected 70 one end of a link 352, the other end of which is connected pivotally to an arm 353 carried on a shaft 284. Arm 353 is connected by screw 354 to the lever arm 283. A link 355 is connected at one end to the arm 283 and at the other end to 75 an extension 356 of lever 288.

Now, when arm 348 is rocked clockwise (as viewed in Fig. 5), lever arms 349 and 351 will be rotated counterclockwise (as viewed in Fig. 2). Lever arm 283, through link 352 and arm 353, will be rotated counterclockwise, and lever arm 288, through link 355, will be rotated clockwise. In the position of the parts shown in Fig. 2, the movement of arm 288 will result only in further collapsing the toggle mechanism 275-287 which has previously been conditioned for collapse by portion 313 of the member 271 which has been shifted to the right. Furthermore, member 293 will be free to be actuated rightwardly until the left end of slot 294 strikes the pin 295, whereupon further movement of lever 288 will cause compression of spring 301.

On the other hand, the counterclockwise rotation of lever 283 will cause the toggle 274-282 in its rigid position to be moved leftwardly (as viewed in Fig. 2) until the right-hand portion 263 of member 262 abuts a selected stop element 259. It will be recalled that this motion is imparted to member 262 through the medium of the anticipator 285. Assume, for example, that the portion 263 abuts the projection 259 of the middle bar 256. Further movement of lever 283 will cause pivot 272 to advance toward the left, while anticipator 285 is arrested by the portion 263, thus causing link 274 to rotate clockwise about the anticipator 285 as a fulcrum and thereby causing the toggle 274-282 to collapse against the pull of spring 276. As the toggle 274-282 thus collapses, the fixed stop 357 of member 264 will approach the right-hand surface of portion 263 at a decelerated rate of speed. After the fixed stop 357 has reached said surface of portion 263, further movement of lever 283 will cause the toggle 274-282 to collapse further, which action is compensated for by the spring 307 and the slidable connection 303, the shoulder 305 having been raised into abutting relation with flange 299. Thus it is observed that by means of the counterclockwise rotation of lever 283, leftward movement is imparted to plate 264, the final part of said movement occurring at a decelerated rate of speed so as to cause stop 357 to come to rest gently against portion 263.

This leftward movement of plate 264 is transmitted through links 322 and 326 and bracket 331 to the track member 332, and then through pivots 334 to the pivoted members 335. Since the strap 337 is movable with rollers 358 mounted on pivots 334 on brackets 335, and since the strap 337 is fixedly connected to saddle 336 and hence fixedly related to the type carriage 158, it is evident that the movement given to plate 264 is transmitted to the type carriage 158. The strap 337 is wrapped around drums 361 and 362 of a spacing mechanism, to be hereinafter described, whereby a predetermined invariable character spacing movement is imparted to the saddle 336 independently of the variable movement just described.

Rightward movement (as viewed in Fig. 2) is imparted to the plate 264 (and hence to track 332) in the following manner. Having reference to Figs. 4, 8, and 15, the direction bar 66 is actuated in response to the third impulse of the five unit code (according to the present embodiment of the invention), through a bell crank 36. The direction bar 66 is shown in Fig. 4 in its leftward or spacing position, thereby holding the lever 316 in its counterclockwise position and the bar 271 in its rightward position. With the bar 271 in its rightward position, the projections 313 and 314 are in the position shown in Fig. 2 wherein

the toggle 275-287 is held in its collapsed position by the projection 313, and the toggle 274-282 is held in its rigid position by the spring 276, and the projection 314 is poised to coact with the cam surface 290.

How, in response to a marking signal during the third impulse interval of the received code combination, the direction bar 66 will be moved to the right (as viewed in Fig. 4) and the lever 316 will be rotated clockwise to impart leftward movement to member 271 which will accomplish two things. First, the lateral projection 314 coacts with cam surface 290 to collapse the toggle 274-282, and the similar projection 313 is moved free of the cam surface 280 to permit spring 279 to straighten the toggle 275-287. Secondly, the cam surface 312 (Fig. 6) cooperates with pin 309 to rock the member 296 clockwise, thereby positioning the shoulder 298 (Fig. 2) in horizontal alignment with the flange 299.

It will be recalled that during the code combination signal interval wherein the third signal impulse determines the position of the direction bar 66, the first and second signal impulses determine the selection of the elevation stop bars 63, 65, and 67, while the fourth and fifth signal impulses determine the selective position of code bars 62 and 64, and hence the positionment of the horizontal movement stop element 254, 255, and 256. Thus, after the foregoing selections have been made in response to a received permutation code combination of signal impulses, the clutch 105 is initiated into operation to effect the operation of arm 348, and hence lever arms 283 and 288. The counterclockwise movement of lever 283 will have no effect on the plate 264 at this time because the toggle 274-282 has been collapsed by projection 314, and pursuant to further counterclockwise movement of lever arm 283, the toggle 274-282 will be further collapsed in the manner previously described in connection with toggle 275-287.

On the contrary, the clockwise rotation of lever 288 will cause the toggle 275-287 in its rigid position to be moved rightwardly until the left-hand portion 263 of member 262 abuts a selected stop element 261. This rightward motion is imparted to member 262 through the instrumentality of anticipator 286. Assuming that the portion 263 abuts the projection 261 of the middle bar 256, further clockwise movement of lever 288 will cause pivot 273 to advance toward the right, while anticipator 286 is arrested by the portion 263, thus causing link 275 to rotate counterclockwise about the anticipator 286 as a fulcrum and thereby cause the toggle 275-287 to collapse against the pull of spring 279. As the toggle 275-287 thus collapses, the fixed stop 359 of the member 264 will approach the left-hand surface of portion 263 at a decelerated rate of speed. After the fixed stop 359 has reached portion 263, further movement of lever 288 will cause the toggle 275-287 to collapse further, which action is compensated for by the spring 301 and the slidable connection 292, the shoulder 298 having been raised into abutting relation with flange 299. Thus it is observed that by means of the clockwise rotation of lever 288, rightward movement is imparted to plate 264, the final part of said movement occurring at a decelerated rate of speed so as to cause stop 359 to come to rest gently against the left-hand portion 263 of member 262.

This rightward movement of plate 264 is transmitted through links 322 and 326 and bracket 331 to the track member 332, and then through pivots 334 to the pivoted members 335. Since, as pre-

viously described, the strap 337 to which the type carriage is attached is movable with the frame comprising track member 332 and pivoted side members 335, this rightward movement given to plate 264 is transmitted to the type carriage. When it is desired to again move the plate 264 leftwardly, a spacing signal is transmitted in the third impulse position of the character code signal, the effect of which is to actuate the direction bar 66 to its left hand position (as viewed in Fig. 4) to rotate the lever 316 counterclockwise and to move the member 271 rightwardly. This rightward movement of member 271 will cause its cam surface 311 (Fig. 6) to cooperate with stud 295 to rock the member 296 counterclockwise, and to cause projection 313 to coat with cam surface 280 (Fig. 2) to collapse the toggle 275-281, thereby conditioning the toggle 274-282.

As indicated hereinbefore, the type carrier 99 is divided horizontally into four sections, each section embracing four vertical rows of characters. Identifying said sections from left to right as 1, 2, 3 and 4; sections 1 and 2 contain lower case or unshift characters, and sections 3 and 4 contain upper case or shift characters. Thus the center line 361 (Fig. 6) between sections 1 and 2 is indicative of the normal position of the type carrier in the unshift or lower case position, so that the type carrier 99 is actuated rightwardly and leftwardly from this center line by means of the knee-action arrangement just described to effect the selection of lower case characters. The center line 361 is shown in Fig. 2 in registry with the printing point, exemplified by the print hammer 362. In this position the stops 259 are effective to control printing from section 2, and stops 261 control printing from section 1.

The center line 363 between sections 3 and 4 is indicative of the normal position of the type carrier in the shift or upper case position, so that the type carrier is actuated rightwardly and leftwardly from this center line by means of the knee-action arrangements (Fig. 2) to effect the selection of upper case characters. The mechanism for shifting and unshifting the type carrier 99 between the center lines 361 and 363 will now be described. As previously mentioned, a plurality of selectable function bars 39 (Fig. 8) are provided for controlling the various functions of the machine being described. The function bars 39 are provided with code projections 364 which cooperate with the series of code bars 62 to 66. The projections 364 are offset to the right or left in coded manner according to the code assigned to the particular function bar 39.

The function bars 39 are mounted pivotally on a shaft 365 (Figs. 8 and 15) and are normally biased toward the code bars 62 to 66 by individual springs 366. The function bars 39 are normally held out of contact or engagement with the code bars 62-66 by a bail 367 (Fig. 15) which is pivotally supported on pivot shaft 365. The bail 367 is connected by a link 368 to the end of an arm 369 secured to a rock shaft 371 suitably journaled in the apparatus. An arm 372 diametrically opposed to arm 369 is also secured to the shaft 371 and is connected at its free end to an eccentric 373 associated with the function clutch 107. As the eccentric 373 is actuated up and down in proper timed relation with signal reception, the shaft 371 will be rocked, and through the toggle action between arm 369 and link 368 the bail 367 is actuated.

Upon the proper setting of the code bars 62 to 66 a function bar 39 will be selected, and as the

bail 367 is initially moved clockwise, the selected function bar 39 will be permitted to fall into the notches in the code bars under the influence of its spring 366. In response to this latter movement of the function bar 39, an interponent 374, which normally reposes on the upper shoulder 375 of the function bar 39, will ride off of shoulder 375 and come to rest on shoulder 376. Then, as the function bar 39 is actuated counterclockwise (as viewed in Fig. 15) the step between shoulders 375 and 376 will urge the interponent 374 leftwardly to perform a function.

In Fig. 15 the interponent 374 is shown as controlling the counterclockwise actuation of the clutch release lever 377 pivotally mounted on pivot 378. As the lever 377 is rotated counterclockwise against the pull of its spring 379, a stud 381 at the lower end thereof cooperates with a cam surface on gate 127 to rotate the gate 127 counterclockwise about its pivot 382 against the pull of its spring 383 to remove the extremity of gate 127 from the path of portion 126 of the line feed clutch 106, thus releasing the clutch 106 for rotation.

Below the interponents 374 is positioned a stripper plate 384 which is pivotally articulated to a lever 385 mounted on a pivot 386. Lever 385 is pivotally articulated to a laterally directed portion 387 (Fig. 16) integral with member 187, previously described. Thus, as member 187 is oscillated by the link 184, the lever 385, through projection 387, is caused to rock to elevate the stripper plate 384 periodically. The interponents 374 are biased downwardly by individual springs 388.

Having reference to Fig. 12, the shift function bar 399 (similar to function bars 39) is shown in the condition of having been selected by the code bars 62 to 66 whereby the interponent 391 therefor is resting on the lower shoulder 376, so that when the function bar 399 is actuated by the bail 367 the interponent 391 will be actuated rightwardly (as viewed in Fig. 12) to cooperate with an arm 392 of a rocker member 393, whereby said member 393 is rocked clockwise. Rocker member 393 is provided with a depending portion 394 by means of which the member 393 is articulated to an intermediate lever 395 mounted on a pivot 396. The lever 395 is, in turn, articulated to the shift-unshift bar 400 by means of a depending portion 397. Thus, in response to the clockwise rotation of member 393, the shift-unshift bar will be actuated leftwardly, as viewed in Fig. 12 (or rightwardly as viewed in Fig. 4).

The "unshift" function bar 398, when operated, will actuate the interponent 399 to impart counterclockwise rotation to rocker member 393 through arm 401 thereof, thereby imparting, through lever 395, rightward movement to the shift-unshift bar 400 (as viewed in Fig. 12). The rocker member 393 is also provided with a further arm 402 which cooperates with an interponent 403 associated cooperatively with an "unshift on space" function bar 404. The "unshift" function bar 398 responds to the unshift code signal, while function bar 404 responds to the space code signal, but both bars 398 and 404 ultimately achieve the same object; that is, shifting the shift-unshift bar 400 to the unshift position.

The shift-unshift bar 400 is provided with two integral depending portions 405 and 406 each of which is notched to receive lateral projections 407 on a member 408 (Figs. 6 and 7). Member 408 is slidably supported on a pair of studs 409 appropriately mounted on the front plate 253. Member 408 is provided integral therewith with a

stud 411 adapted to cooperate with a slot 412 in an actuating bar 413 which is slidably guided in a pair of brackets 414 secured to the front plate 253. Actuating bar 413 has pivotally connected thereto a pair of links 415 and 416. Link 415 is pivotally connected to the extremity of a lever arm 417 mounted pivotally on the stud 284, and link 416 is pivotally connected to the extremity of an arm 418 of lever 349, (Figs. 2 and 6) pivotally mounted on the stud 289. Arm 417 is provided with a stud 419 which cooperates with a slot 421 in arm 418 so that as pivotal motion is imparted to arm 418 this motion will be transmitted through stud 419 to arm 417.

Pivots connected to pivot 324 of toggle 322—326 and depending therefrom, is an arm 422. The lower extremity of arm 422 is provided with a forwardly directed flange portion 423 and a rearwardly directed stud 424. The stud 424 is adapted to be slightly guided vertically in a slot 425 in a guide member 426 secured to the front plate 253. Similarly, an arm 427 is pivotally articulated to the toggle 321—325 at pivot 323, and is provided at its free end with a forwardly directed flange portion 428 and a rearwardly directed stud 429 which cooperates with a slot 431 in a guide member 432 secured to the front plate 253.

With the arrangement just described vertical movement is applied to actuating bar 413 by lever arms 417 and 418, as will presently appear, and horizontal motion is applied to actuating bar 413 by the shift bar 400 through the instrumentality of member 408. In Fig. 6 the type carrier 99 is shown in its "Letters" position, whereat the center line 361 is in register with the printing point. In this condition, the toggle 321—325 is collapsed and the toggle 322—326 is extended. To shift the type carrier 99 to the "Figures" position whereat the center line 363 is brought into registry with the printing point, the following mechanical movements take place.

The "shift" signal is received by the selector mechanism and the code bars 62 to 66 are set accordingly. The shift function lever 389 (Fig. 12) is selected so as to cause the interponent 391 to rest on the shoulder 376 so that actuation of interponent 391 will rock the member 393 clockwise to impart rightward movement (as viewed in Figs. 2 and 6) to the bar 400. This rightward movement of bar 400 is imparted through portions 405 and 406 to the member 408 and, in turn, through stud 411 to the actuating bar 413. On the other hand, vertical motion is imparted to the actuating bar 413 in the following manner: At a predetermined time in the cycle the clutch for controlling the oscillation of shaft 178 is tripped, and the shaft, in rocking, imparts, through arm 348, first a counterclockwise rotation to lever 349 which through its arm 418 and pin and slot connection 419—421 imparts clockwise movement to arm 417. Through the aforesaid motion imparted to arms 417 and 418, the links 415 and 416, respectively, are elevated, which motion is imparted to actuating bar 413. By the proper timing of said vertical and horizontal motions the actuating bar 413 is, in response to the "shift" code signal, first elevated to a position slightly above the level of projection 423 and then moved rightwardly to position the extremity 433 directly over the projection 423, whereupon, in response to the reverse movement of shaft 178, downward movement is imparted to the actuating bar 413 thereby pulling the arm 422 downwardly to collapse the toggle 322—326.

By thus collapsing the toggle 322—326, the frame comprising brackets 329 and 331 and the bar 332 is moved leftwardly thereby straightening the toggle 321—325, and as a result thereof the type carrier 99 will have been moved to bring the center line 363 into line with the printing point, exemplified by the print hammer 362. At the conclusion of this function the arms 422 and 427 will have assumed positions reverse to that shown in Fig. 6 and the extremity 433 will be resting over the projection 423, so that in order to effect the unshift function the actuating bar 413 will first be elevated to a position slightly above that to which the projection 428 was just raised by the straightening of toggle 321—325, and then moved leftwardly to bring extremity 434 of bar 413 over the projection 428 whereby upon downward movement of bar 13 the toggle 321—325 will be collapsed and the bar 332 (and type carrier 99) will be moved rightwardly to bring the center line 361 again in registry with the printing point. Of course, the unshift function was initiated by the receipt of the unshift code signal pursuant to which the unshift function bar 398 (Fig. 12) was selected, whereupon interponent 399 was actuated to rock the member 393 counterclockwise to impart, through lever 395, rightward movement to shift bar 400 as viewed in Fig. 12 (leftwardly as viewed in Fig. 6). This leftward movement of shift bar 400 transferred to member 408 and the actuating bar 413 combined with the vertical movement imparted to bar 413 will cause the extremity 434 to be superposed above the projection 428 to effect the collapsing of toggle 321—325 to move the bar 332, and hence type carrier 99, rightwardly (as viewed in Fig. 6) to bring the center line 361 into registry with the printing point. Due to this latter operation the shift mechanism will assume the position shown in Fig. 6.

The printing hammer arrangement is illustrated in Figs. 21, 22 and 23 and comprises the print hammer 362 and the operating mechanism therefor, now to be described. The print hammer support comprises a plate 435 on which are mounted a pair of grooved rollers 436 and 437, and a grooved roller 438 which are adapted to cooperate with a track member 439 which is supported by a pair of brackets 441 bolted to the front plate 253. Fixedly connected to the inside face of the supporting plate 435 in any suitable manner (for example, to the roller stud shafts as shown) is an angle bracket 442 the horizontal leg of which is securely fastened by means of bolts 443 to a flexible metallic strap 444. As more clearly shown in Fig. 1, the strap 444 extends around a pair of rollers 445 and 446 rotatably carried at the extremities of the track member 439. The strap 444 is wrapped around the pair of spacing drums 361 and 362 of the spacing mechanism to be hereinafter described.

The supporting plate 435 is provided at its lower end with a pair of forwardly directed portions 449 and 451 into which is journaled a pivot shaft 452 on which are pivotally mounted a print hammer conditioning lever 453 and a print hammer operating lever 454. Suitably guided for sliding relation with the supporting plate 435 is an actuating plate 455, which is provided with integral lugs 456 and 457 adapted to slidably engage the upper and lower edges, respectively, of a vertically reciprocable operating bar 458. The bar 458 is slidably guided for vertical reciprocation by a pair of guide brackets 459 and 461 adapted to cooperate with each end of said bar

458. A tie bar 462 is provided between brackets 459 and 461.

Near each end of the operating bar 458 there is provided an aperture 463 through which extends the end of one arm of a pair of operating levers 464, each being mounted on a pivot shaft 465 journaled in a bracket 466 fixed to the front plate 253. The end of the other arm of each of the levers 464 is pivotally articulated to the upper extremity of an associated operating slide 467 10 dually guided by a bracket 468 (fastened to plate 253) and by the shaft 178. Slide 467 is provided with a slot 469 to permit vertical slidable motion on shaft 178. Slide 467 is also provided with a pair of cam follower rollers 471 and 472 arranged on opposite sides of shaft 178. Rollers 471 and 472 are adapted to cooperate with a cam 473 fixed on shaft 178. Cam 473, as illustrated in Fig. 22, is contoured to impart positive cam action in both directions to the reciprocable slide 467, it being recalled that shaft 178 has rocking motion imparted to it by clutch 105 (Fig. 13).

Cooperating with lug 456 is the toe 474 of the conditioning lever 453. Lever 453 is U-shaped at its pivotal end to provide a dual bearing on pivot shaft 452 and also to provide a spring post 475 to which is secured one end of a printing spring 476, the other end of which is secured to a spring post 477 (Fig. 21) integral with the supporting plate 435. Under the action of the spring 476, the lever 453, through its extension 478, normally abuts a stop 479 carried on the supporting plate 435. Stop 479 is preferably made of leather, or like sound absorbing material. With the lever 453 in said normal position, the toe 474 is held in operative relation with lug 456.

The conditioning lever 453 is also provided with a laterally extending portion 481 (Figs. 21 and 22) against which the lever 454 is held by a spring 482 stretched between a spring post 483 on lever 454 and an eyelet 484 on lever 453. The supporting plate 435 is provided with a forwardly directed flange 485 to which is secured a pivot shaft 486 for pivotally supporting a latch member 487. Latch 487 is normally spring biased counterclockwise by a spring 488 distended between an eyelet on latch 487 and a spring post 489 on the supporting plate 435, whereby the laterally directed end 491 of latch 487 is held against a surface 492 (of latch 487) concentric with the pivot shaft 452. Surface 492 terminates in a latching shoulder 493 adapted to cooperate with the end 491 of latch 487.

The actuating plate 455 is provided with an integral bracket portion 494 which carries an adjustable striker screw 495 adapted to cooperate with the latch member 487 to effect the disengagement of portion 491 of latch 487 from the shoulder 493, as will presently appear. The print hammer 362 is pivotally connected by pivot 496 to the operating lever 454. The print hammer 362 is guided by a guide member 497 secured to the supporting plate 435. The operating lever 454 is guided by a guide member 498 also secured to the supporting plate 435.

In the operation of the printing mechanism, the operating bar 458 is first actuated upwardly, through the instrumentality of the cam 473 and interconnecting linkage, to rotate the lever 453 clockwise (Fig. 22) until the latch 487, through its edge 491, engages the shoulder 493 of lever 453. In this portion of the printing operation the printing spring 476 becomes tensioned, and the lever 454 is held against portion 481 of lever 453 by the spring 482. In this manner the print

hammer 362 is poised in front of the selected type character 155, so that upon the downward stroke of the actuating bar 458 the actuating plate 455 will move therewith and through the instrumentality of the striker screw 495 carried on bracket 494 the latch 487 will be disengaged from the shoulder 493 thereby releasing the energy stored up in the spring 476, and accordingly, lever 453, through lateral portion 481 will transfer this energy to the lever 454 and hence to print hammer 362 to impinge the type pallet 155 against the platen 499. The actuating bar 458 having returned to the normal position shown in Fig. 22, the counterclockwise movement of lever 453 by the spring 476 will be arrested by the toe 474 striking the lug 456, but the lever 454 and print hammer 362 will, however, continue their motion to effect what is generally termed overthrow printing.

The print hammer 362 is constructed, as shown in Fig. 23, with a swivelled or yieldable hammer head 501 to prevent breakage of type pallets 155 due to the rapid shifting of the type carrier 99 from one pallet position to another. When the type carrier 99 is rapidly shifted either horizontally or vertically facilities are provided to permit this movement of the type carrier irrespective of the relative position of the print hammer therewith; that is, the type carrier may start its motion before the print hammer is fully withdrawn, thus precluding damage to the type elements because of the swivelled hammer head. As shown in Fig. 23, the print hammer 362 comprises a main portion 502 and a head portion 501. The portions 501 and 502 are provided with aligned bores in which is inserted a coiled spring 503 which is retained in the bores of portions 501 and 502 by rivets 504 and 505, respectively. The head portion 501 is grooved at 506 and the portion 502 is rounded to fit therein. The spring 503 thereby functions to hold portions 501 and 502 together and constantly in axial alignment. When the swivelled head 501 is deflected to the positions 507 and 508, the spring 503 rapidly returns the parts into alignment.

The manner of actuating the printing mechanism to achieve character spacing will now be described, reference being had to Figs. 1, 24, 25, 26, 27 and 28. As previously described, the type carrier mechanism and the print hammer mechanism are each attached to separate steel bands 337 and 444, respectively, which are adapted to be wound around drums 361 and 362. The drums 361 houses a carriage return spring (not shown) which is operated according to the old and well known principle of being wound up as the type carriage is being advanced step-by-step to store up energy therein in readiness to return the carriage in response to a carriage return signal. The step-by-step movement is imparted to the type carrier and print hammer mechanism by the mechanism shown in Figs. 24 to 28. The periphery of each of the drums 361 and 362 is provided with a pair of grooves for the steel bands 337 and 444.

Power for operating the spacing mechanism is derived from the main shaft 27 (Fig. 24) through the spacing clutch 108 (Fig. 30) with which is associated an eccentric cam 511 (Fig. 24). Operatively related to cam 511 is an eccentric strap 512 which is pivotally articulated to a lever 513 mounted rockably on a pivot shaft 514. At its free end lever 513 is pivotally articulated to one flange of a U-shaped rocker member 515 mounted pivotally on a shaft 516 (Fig. 25).

On the other flange of the rocker member 515 are pivotally mounted a pair of pawl members 517 and 518 adapted to cooperate with a ratchet wheel 519 integrally associated with the spacing drum 362. Pawl member 518 is normally biased into operative engagement with the ratchet 519 by a spring 521. Pawl 517 is normally biased into engagement with ratchet 519 by a spring 522 which is stretched between said pawl 517 and the pawl 518, as shown in Fig. 25. A pair of thin plates 523 are riveted to the pawl 518 and are disposed on each side of the pawl 517 to serve as a guide means therefor.

As the member 515 is rocked, the pawls 517 and 518 function alternately to advance the ratchet wheel 519 clockwise, as viewed in Fig. 25. Specifically, the clutch 108 performs two spacing operations per complete revolution of the clutch. For example, during one-half revolution of the clutch 108 the member 515 will be rocked counterclockwise (as viewed in Fig. 25) to raise pawl 518 to rotate the ratchet 519 a predetermined amount in a clockwise direction sufficient to move the straps 337 and 444 one character space. During this revolution of clutch 108 the pawl 517 is moved backwardly along the periphery of the ratchet 519 so that during the next one-half revolution of the clutch 108 the member 515 will be rocked clockwise to raise pawl 517 and lower the pawl 518. The raising of the pawl 517 will impart clockwise rotation to ratchet 519 to effect character spacing movement of the straps 337 and 444.

Integral with the ratchet wheel 519 and drum 362 is an arm 524 having a pin 525 extending laterally therefrom at the free end of said arm. Thus, through the pin 525 the arm 524 cooperates with the plunger 526 of a dash pot shock absorbing device 527. Plunger 526 carries at its free end a guide roller 528 which rides in a slot 529 in a guide bracket 531. As the ratchet 519 is rotated clockwise by the spacing pawls 517 and 518 during the printing of a line, the arm 524 is also rotated with the ratchet, the carriage return spring in the drum 361 being wound during the process. The arm 524 will be thus rotated to a position exemplified by the dotted position 532, and in response to the carriage return signal (as will presently appear) the pawls 517 and 518 will be disengaged from the ratchet 519 whereupon the drum 362 (including ratchet 519 and arm 524) will be rotated counterclockwise by the carriage return spring until the pin 525 on arm 524 strikes the plunger 526, after which the momentum imparted to the drum 362 will cause the plunger 526 to be moved rightwardly with a decelerated motion due to the dashpot action to the dot-and-dash line position 530 shown in Fig. 25. Mounted pivotally on the bracket 531 is a lever arm 533 having a laterally directed extremity cooperating with the plunger 526 whereby under the action of a spring 534 the plunger 526 will be withdrawn from the dashpot 527, upon resumption of printing of a new line, until the roller 528 reaches the left end of slot 529.

In Figs. 26, 27 and 28 the mechanism for accomplishing the carriage return and back space functions is shown. Mounted on the pivot shaft 516 and positioned in front of the rocker member 515 are three bell crank levers 535, 536 and 537 (Fig. 26), each having a depending portion to which is connected an individual biasing spring 538. Each spring 538 biases its associated lever clockwise against an up-stop 539. The extremi-

ties of the horizontal arms of the bell cranks 535, 536 and 537 are shown at 541, 542 and 543, respectively. Lever 535 is positioned on its vertical arm with a stud 544 adapted to span pawl 517 and arms 523 of pawl 518 to effect the disengagement of pawls 517 and 518 from ratchet 519, as will presently appear.

Appropriately mounted in the framework of the apparatus is a bracket 545 which carries a pivot 546 on which are mounted pivotally the carriage return function lever 547 and the back space function lever 548. Function levers 547 and 548 are similar to function lever 377 shown in Fig. 15 and are actuated in a similar manner through interponents 549 and 550 similar to interponent 374, shown in Figs. 8 and 15. Pivotally articulated to the lower end of the levers 547 and 548 are bell crank levers 551 and 552, respectively, which are mounted on a pivot 553 (Fig. 28) suitably carried in the apparatus.

In response to the receipt of the carriage return code signal, the interponent 550 will be actuated leftwardly (Fig. 27) to impart counterclockwise rotation to the carriage return lever 547 which, in turn, will impart clockwise rotation to the bell crank 551 (Fig. 28). Then through the free end of the horizontal arm of bell crank 551, counterclockwise rotation will be imparted to the lever 536 (through its extremity 542), Fig. 26. Lever 536 is provided with a laterally disposed portion 553 which cooperates with the bell crank lever 535 such that counterclockwise rotation imparted to lever 536 will be imparted to the lever 535. As previously described, the lever 535 is provided with a stud 544 by means of which the pawls 517 and 518 are withdrawn from the ratchet 519 to permit the performance of the carriage return function. The lever 536 is also provided with a projection 554 which contacts with a hooked arm 555 of a back space pawl 556 to disengage the back space pawl 556 from the ratchet 519 during the carriage return movement. The lever 536 is further provided with a latch projection 557 which cooperates with a latch 558. The latch 558 is normally biased counterclockwise (Fig. 26) by a spring 559 so that when the lever 536 is rotated to effect the carriage return operation it will become latched up to insure the completion of the carriage return function. To effect the unlatching of latch 558 from the lever 536 when the carriage return function is completed, a projection 561 carried on the ratchet 519 cooperates with an arm 562 on the latch 558 to rotate the latch 558 clockwise to effect its disengagement from lever 536.

Mechanism is provided for back spacing the printing elements in a step-by-step manner, and comprises the back space function lever 548 which in response to the back space code signal is rotated counterclockwise (Fig. 27) to impart clockwise rotation to bell crank lever 552. Lever 552, through extremity 543, will rotate lever 537 counterclockwise (Fig. 26). Lever 537 is provided with a laterally directed extremity which cooperates with the vertical arm of the lever 535 to impart counterclockwise rotation to said lever 535 which, through its stud 544, will disengage the pawls 517 and 518 from the ratchet wheel 519. The lever 537 is further provided with a depending portion carrying a pin or stud 563 adapted to cooperate with the pair of back space pawls 556 and 564. The lever 556 is provided with an arm having a cam surface 565, and the lever 564 is provided with an arm having a cam surface 566. Levers 556 and 564 are normally biased counter-

clockwise by individual springs 567 and 568, respectively, whereby the cam surfaces 565 and 566 are normally held against the pin 563. Thus, when the lever 537 is rotated counterclockwise by the back space function lever 548 the cam surfaces 565 and 566 coact with the pin 563 in such a manner that the pawl teeth 569 and 571 of pawls 556 and 564, respectively, are actuated in escapement manner to permit the ratchet wheel 519 to rotate backward (that is, counterclockwise, Fig. 26) under the control of the carriage return spring one step or tooth for each oscillation of the lever 537. Specifically, the action is as follows: When the lever 537 rotates counterclockwise, the pin 563 permits pawl 564 to rotate counterclockwise, and rotates the pawl 556 clockwise, whereby the tooth 571 is positioned in the middle of the ratchet tooth next to the ratchet tooth engaged by the tooth 569. However, the tooth 571 is brought into engagement with the ratchet tooth before the tooth 569 is withdrawn, to thus provide an overlap and to prevent uncontrolled escape of the ratchet wheel 519. Then, when the lever 537 is rotated clockwise the tooth 569 is brought into engagement with the ratchet teeth before the pawl tooth 571 is withdrawn to permit the ratchet wheel 519 to rotate backward the second one-half step.

The line feed mechanism according to the present invention is illustrated in Fig. 33 and comprises a gear 575 fixedly related to the platen 499, and a pair of rack members 576 and 577. Having reference to Fig. 29 the line feed clutch is shown at 106 and is of the construction illustrated in Figs. 31 and 32. The gear 575 rotates with the platen 499 and the racks 576 and 577 are adapted to be alternately engageable with the teeth on the gear 575, with a slight overlap of engageability being provided, so as to impart substantially uniform rotative motion to the gear 575 and platen 499. The present mechanism obviates the jerky movement inherent in pawl and ratchet mechanisms and imparts to the platen a smoothly accelerated and decelerated motion.

The racks 576 and 577 are connected to eccentrics 578 and 579, respectively, operatively related to the line feed clutch 106 (Fig. 29), and power for operating said racks is derived from the main shaft 27 through said clutch. The eccentrics 578 and 579 thus control the reciprocatory motion of the racks 576 and 577. As illustrated in Figs. 33 and 34, the racks 576 and 577 are adapted to be rocked on a movable pivot 581 comprising a friction roller 582 cooperable with slots 583 and 584 in said rack members. The friction roller 582 is carried on the vertical arm of a bell crank lever 585 pivotally mounted on a pivot stud 586 fixed to the side frame of the apparatus. The bell crank 585 is normally biased clockwise about pivot 586 by a spring 587 against an adjustable stop 588.

Upon rotation of the eccentrics 578 and 579, a combination of rocking motion and vertically reciprocating motion is imparted to the racks 576 and 577. When the racks 576 and 577 are rotated clockwise about the pivot roller 582 by their respective eccentrics 578 and 579, the teeth on the racks 576 and 577 will engage the teeth of gear 575. To permit the rack teeth to mesh with the gear teeth under pressure, the fulcrum pivot 582 is made movable so that slight counterclockwise movement is imparted to bell crank 585 thus increasing the tension of spring 587.

In the performance of the line feed operation

the line feed code signal is received by the selector mechanism to effect a setting of the code bars 62 to 66 to select the line feed function control lever 591 (similar to lever 39) which through its interponent 592 (Fig. 29) actuates the line feed clutch release lever 377 (Fig. 15) which as previously described initiates the rotation of clutch 106 which controls the rotation of the eccentrics 578 and 579. As shown in Fig. 33 the eccentrics 578 and 579 are arranged to actuate the racks 576 and 577 in an alternate manner, as described above.

The ribbon feed mechanism is shown in Fig. 1 as comprising a pair of ribbon spool means 593 and 594 for winding the inking ribbon 595 from one spool to another, and automatic means for reversing the direction of movement of the inking ribbon. As indicated in Figs. 13 and 18, the ribbon mechanism embodies a pair of ribbon spool platforms 192 and 219 for supporting the ribbon spools 593 and 594, respectively. The platform 192 is supported pivotally on the stud shaft 193 secured to the side plate 171 and is provided with a depending projection 596 which is pivotally connected to the link 191. The platform 219 is similarly supported pivotally on a stud shaft 597 (Fig. 18) secured to the side plate 170 and is similarly provided with a depending portion 598 which is pivotally connected to the link 218. Thus through bell cranks 188 and 217, links 184 and 207, levers 182 and 206, links 181 and 205, and arms 179 and 204, power is imparted to the platforms 192 and 219 by the shaft 178.

As shown in Fig. 37, the ribbon spool 594 is mounted on a spindle 599 having an integral flange 601. Disposed between flange 601 and the platform 219 is a felt or leather washer 602 (or like material). Between the bottom surface of platform 219 and a feed ratchet wheel 603 is a washer 604 of leather, felt or like material. On the lower side of the ratchet 603 is placed a dished portion 605. Pinned to the lower end of the spindle shaft is a collar 606, and a compression spring 607 is provided between the flange 601 and collar 606 to clamp together all of the aforesaid interposed members. Housed within the dished member 605 is a circular spring element 608 (Fig. 42) the ends of which are adapted to cooperate with laterally disposed projections 609 and 611 on the ratchet 603 and dished member 605, respectively. The member 605 is provided with an oblong hole adapted to fit the flattened portion of the spindle 599.

The reel 593 is operably related to the platform 192 (Fig. 36) in a manner identical with the way the reel 594 is related to the platform 219 (Fig. 37). The ratchets 603 and 612 are in the form of inverted cups having serrated edges. Cooperating with the toothed edge of each ratchet 603 is a pair of pawl members 613 and 614 which are supported pivotally upon a stud shaft 615 secured to the side frame below the pivot shaft 193. The pawls for ratchet 603 are similarly pivoted on a stud shaft 616 (Fig. 18). The pawls 613 and 614 are normally biased into cooperative engagement with the ratchets by means of springs 617 and 618, respectively.

Having reference to Figs. 38 and 39, the relative position of pivot shafts 193 and 615 is such that when the platform 192 is rocked by the link 191, clockwise rotation is imparted to the ratchet 612 upon the downward stroke of the platform 192, as exemplified by the relative position of the free end of the pawl 614 with respect to the ratchet 612 in Figs. 38 and 39. Upon the upward

stroke of the platform 192 further clockwise motion is imparted to the ratchet 612. To accomplish this result the end of the pawl 613 is reverted so that upon the downward stroke of the platform 192 (and hence ratchet 612) the pawl 613 will pick up a tooth and upon the upward stroke the pawl 613 will act to impart clockwise rotation to the ratchet 612. With this arrangement utilizing a pair of pawls, smooth rotation of the ratchet will ensue.

Mechanism is also provided for automatically reversing the direction of the ribbon feed from one spool to the other. Having reference to Fig. 35, the inking ribbon 595 extends from the spool 593 around a guide roller 619 mounted on the platform 192. Ribbon 595 is then threaded through the bifurcated extremity 621 of a ribbon reverse lever 622, mounted pivotally at 623 on the platform 192. Lever 622 is normally biased clockwise (as viewed in Fig. 35) by a spring 624. Lever 622 is provided with a projection 625 which cooperates with a lever 626 mounted pivotally on a rocker detent bar 627 carried on a pivot 628 appropriately positioned in the apparatus. Lever 626 is normally biased counterclockwise (as viewed in Fig. 36) by a spring 629. Bar 627 coacts with a spring detent 631. A lever 632, similar to lever 626, is pivotally mounted at the opposite end of the bar 627 in cooperative relation with a ribbon reverse lever 633 (comparable to lever 622) pivotally carried on the platform 219. The right end of the bar 627 cooperates with a detent spring 634.

Pawl 613 is provided with an arm 635 the extremity of which is disposed below the extremity of an arm 636 integral with the pawl 614. Pawl 614 is also provided with an arm 637 oppositely disposed to arm 636 which cooperates with a shoulder 638 on the lever 626. Similarly, pawl 641 (comparable to pawl 613) is provided with an arm 642 the extremity of which is disposed below the extremity of an arm 643 integral with the pawl 644 (comparable to pawl 614). Pawl 644 is also provided with an arm 640 oppositely disposed to arm 643 which cooperates with a shoulder 646 on the lever 632. The projection 625 of the ribbon reverse lever 622 cooperates with a shoulder 639 on the lever 626. Similarly, a like projection 625 of the ribbon reverse lever 633 cooperates with a shoulder 645 on the lever 632. A rivet 641 is provided near each end of the ribbon 595 so that when the supply of ribbon is nearly exhausted from reel 593 (or reel 594), the rivet near the end of the ribbon from the exhausted reel will fail to pass through the slit in the bifurcated end 621 of the ribbon reversing arm or lever 622 or 633.

The ribbon reverse mechanism according to the present invention operates as follows: Assuming that the pawls 613 and 614 are in engagement with the ratchet wheel 612 (Fig. 36) and the pawls 641 and 644 are out of engagement with the ratchet wheel 603 (Fig. 37), the movement of the ribbon 595 (upon oscillation of the platform 192) will be pulled from reel 594 and wound around the reel 593. When the supply of ribbon from wheel 594 is nearly exhausted the rivet near the end of the ribbon thereat will advance toward the slit in the bifurcated end of the ribbon reverse lever 633. Upon further rotation of reel 593 the rivet will compel rotation of the ribbon reverse lever 633 in a clockwise direction (leftward in Fig. 37). Thus, during the downward stroke of platform 219 the projection 625 of lever 633 will slide along the

75

connection 664 to, in turn, disengage the driven

right edge of lever 632 until it subsequently engages the shoulder 645, whereafter, upon the upward stroke of the platform 219 the lever 632 will be lifted by the lever 633 to permit the springs of pawls 641 and 644 to bring said pawls into engagement with the ratchet 603. Furthermore, the lifting of the lever 632 in this manner will cause the member 627 to be rocked counterclockwise, whereby the shoulder 638 of the lever 626 will act upon the arm 637 to withdraw the pawl 614 from the ratchet 612. At the same time, the arm 636 of pawl 614 will act upon the arm 635 to withdraw the pawl 613 also from the ratchet wheel 612. Upon further oscillations of the platforms 612 and 219, the reel 594 will take over and the ribbon 595 will be pulled from reel 593 and wound around reel 594. The spring 608 provides a yield between the ratchet and ribbon reel in the event of a deterrent in the movement of the ribbon, thus preventing breakage of the ribbon.

A modified form of character spacing device is shown in Figs. 47 to 50, inclusive, and comprises a power driven spacing means. Fixed to the main operating shaft 178 (Fig. 49) is a gear 651 which meshes with a gear 652 fixed to a shaft 653 journaled in brackets 654 and 655 (Fig. 47). The driving portion 656 of a grab clutch is fixed to the shaft 653 and cooperates with a driven portion 657 which is an integral part of a sleeve 658 slidably mounted on the shaft 653. Also integral with the sleeve 658 is a pinion gear 659 which meshes with a gear 661 integrally associated with the drum 362.

The sleeve 658 is provided adjacent the toothed portion 657 with a groove 662, and cooperating with the groove 662 is a forked member 663 which is pivotally articulated at 664 to a bracket 665. A latch 666 pivoted at 667 cooperates with the forked member 663 to hold the driven member 657 of the clutch disengaged from the driving member 656. A spring 668 normally biases the latch 666 clockwise (as viewed in Fig. 47). The latch 666 extends through a slot 669 in the latch 663 and cooperates with a latch trip element 671 secured to the periphery of the drum 362 such that when the carriage return signal is received and the carriage return function is initiated the drum is rotated counterclockwise (as viewed in Fig. 50) until the element 671 strikes the latch 666 whereupon latch 666 is disengaged from the forked member 663 and the spring 668 is allowed, through the instrumentality of the forked member 663 and groove 662, to draw the driven member 657 of the clutch into engagement with the driving member 656 preparatory to again initiating the character spacing operation which is controlled by the character spacing clutch (comparable to clutch 108) associated with the gear 651.

The carriage return function is effectuated through the function lever 672 which is pivoted at 673 and biased normally clockwise by a spring 674. The function lever 672 is actuated by an interponent 374 in the manner described in connection with the other functions. Assuming that the clutch 656-657 is engaged for character spacing and that it is desired to perform the carriage return operation the interponent 374 is actuated (leftwardly as viewed in Fig. 49), as previously described, to rotate the lever 612 counterclockwise against the action of spring 674. In response to this movement of lever 612 a push rod 675 is actuated forwardly (as viewed in Fig. 47) to pivot the forked member 663 about the pivotal connection 664 to, in turn, disengage the driven

portion 657 of the clutch from the driving portion 656, thereby releasing the drum 362 to the pull of the carriage return spring until the drum 362 will have rotated sufficiently in the opposite direction to permit the element 671 to trip or disengage the latch 666 from the member 663.

Although a preferred form of the invention has been disclosed and described herein, it is obvious that changes may be made in the details set forth without departing from the essentials of the invention.

What is claimed is:

1. In a recorder, a platen, a type carriage, a character spacing mechanism for effecting relative movement between said platen and said type carriage, signal responsive means, stop elements selectively controlled by said signal responsive means, knee-action means comprising anticipator means for impinging against selected stop elements to impart variable movement to said type carriage independently of said spacing mechanism to position a type according to the record to be made, and means cooperable with said platen to effectuate a printing operation.

2. In a recorder, printing instrumentalities comprising a platen and a type carrier movable with respect to each other, printing means cooperable with said type carrier to produce a printed record, selecting means comprising selectively controlled stop elements for determining the character to be recorded, and knee action instrumentalities comprising an anticipator means to be impinged against selected stop elements to effectuate the selection of the character to be recorded.

3. In combination, a coordinately movable member, a signal responsive means, a plurality of stop means selectively controlled by said signal responsive means for determining the extent of movement of said member in predetermined directions, power means, and a corresponding plurality of knee-action means operatively connected between said member and said power means, each of said knee-action means comprising anticipator means for impinging against the selectively conditioned stop means whereby the movements of said member by said power means are decelerated prior to arrestment of said member by said stop means.

4. In a printing telegraph apparatus, a type carrier movable under certain operating conditions from a normal position in either of two directions, drive means, a plurality of pairs of stops for said carrier for enabling varying degrees of movement thereof in either direction, means operable in response to signal code combinations to select a predetermined pair of said stops to enable a predetermined amount of movement of said type carrier, and a pair of cushioning means, each of said cushioning means comprising an anticipator means for impinging against said selected stops, whereby the movement of said carrier by said drive means is decelerated prior to the arrestment of said carrier by said stops.

5. In a printing telegraph apparatus, a type carrier, type carrier supporting means movable under certain operating conditions from a normal position to either of two directions, drive means, a plurality of pairs of stops for said supporting means for enabling varying degrees of movement thereof in either direction, means operable in response to signal code combinations to select a predetermined pair of said stops to enable a predetermined amount of movement of said supporting means, knee-action devices operatively connected

between said supporting means and said drive means, each of said knee-action devices comprising an anticipator means for impinging against said selected stops, and abutting means on said supporting means for also impinging against said selected stops, whereby the movement of said supporting means by said drive means is decelerated between the times of contact of said anticipator and said abutting means with said stops.

6. In a recorder, a type carrying means movable to form character spaces, a reciprocable track member for supporting said type carrying means, drive means, signal controlled means, stop bars selectively controlled by said signal controlled means for enabling varying degrees of reciprocation of said track member, knee-action means connected to said drive means, said knee-action means comprising anticipating means for impinging against selected stop bars, and abutting means associated with said track member for also impinging against selected stop bars, whereby the movement of said track member by said drive means is decelerated between the instants of contact of said anticipating means and said abutting means with said stop bars.

7. In a recorder, a stationary frame, a carriage movable to form character spaces, a plurality of type elements mounted on said carriage, signal responsive means on said stationary frame, stop elements selectively controlled by said signal responsive means, knee-action means between said carriage and said signal responsive means, said knee-action means comprising anticipator means for impinging against said stop elements and acting thereby to select the type element to be operated, and printing means for effectuating the operation of said type element, said printing means comprising a yieldable hammer head, whereby movement of said carriage is facilitated.

8. In a telegraph printer, printing mechanism comprising a type carriage and a print hammer means, a platen, spacing mechanism for effecting a relative fixed character spacing movement between the printing mechanism and the platen, signal responsive means, stop elements selectively controlled by said signal responsive means, and knee-action means comprising anticipator means for impinging against said stop elements and acting thereby to supervene said spacing means to impart variable multi-directional movement to said type carriage to effectuate its selective position, whereby printing is effected by said print hammer means.

9. In a telegraph printer, a type carrier, a print hammer means, a spacing mechanism for imparting uniform character spacing movement to said type carrier and said print hammer means, a first strap operatively associated with said mechanism, said type carrier attached to said first strap, a second strap operatively associated with said mechanism, said print hammer means attached to said second strap, strap guide means fixedly positioned for guiding said second strap, strap guide means movably positioned for guiding said first strap, signal responsive means, stop elements selectively controlled by said signal responsive means, and yieldable means cooperable with said last recited strap guide means comprising instrumentalities to be impinged against selected stop elements to impart variable horizontal movement to said type carrier, whereby variable shifting movement of said type carrier is facilitated independently of said uniform character spacing

movement to effect the selective positionment of a type character.

10. In a telegraph printing apparatus, signal controlled means, a type carrier, a plurality of stop elements controlled by said signal controlled means for controlling the extent of movement of said carrier in predetermined directions, a shaft, power means for imparting a rocking motion to said shaft, attrahently moving elements operatively connected to said shaft, a corresponding plurality of yieldable means operatively connected between said carrier and said attrahently moving elements, said yieldable means comprising anticipator means for impinging against selected stop elements, whereby the movements of said carrier are decelerated prior to the stopping of said carrier by said stop elements.

11. In a recorder, a type carriage comprising a plurality of characters arranged in lower case and upper case groups, permutation means responsive to received code combinations of selecting conditions for selecting a character in each of said groups, toggle shift means for case shifting said carriage, one toggle shift means associated with each of said groups, common actuating means for both of said toggle shift means, means for maintaining said common actuating means in a horizontal position during the cycle of movement of said common actuating means, and means controlled by said permutation means for positioning said common actuating means to render said actuating means effective to actuate said toggle shift means selectively, whereby selection of characters from either of said groups is effectuated.

12. In a recorder, a stationary frame, a type carriage, a plurality of rows of type elements mounted on said carriage, supporting means for said type carriage, signal responsive means on said stationary frame, stop means selectively controlled by said signal responsive means, knee-action means comprising anticipator means cooperable with said stop means to elevate said carriage to selected ones of said rows, abutting means associated with said carriage supporting means, whereby the movement of said supporting means is decelerated between the time of contact of said anticipator means and said abutting means with said selected stop means, cooperating latch means associated with said knee-action means and said abutting means, and camming means cooperable with said latch means during said elevating operation to latch said carriage in elevated position.

13. In a recorder, power means, a type carrier, said type carrier being provided with character elements divided into two principal groups, each of said groups being divided into two further groups, signal responsive means, a member selectable under the control of said signal responsive means, toggle means controlled by said selectable member for operating said type carrier to facilitate selection of a character element from one or the other of said principal groups, stop elements selectively controlled by said signal responsive means for determining the selection of said character element from one or the other further

groups of the selected principal group, and knee-action means comprising anticipator means for impinging against the selected stop element, whereby the movement of said type carrier by said power means is decelerated prior to arrestment of said type carrier by said selected stop element to effectuate the selection of said character element.

14. In a printing telegraph apparatus, a type carrier movable under certain operating conditions from a normal position in either of two directions, drive means therefor, signal responsive means, a plurality of pairs of stops for said carrier for enabling varying degrees of movement of said carrier in either direction, means controlled by said signal responsive means to select a predetermined pair of said stops to enable a predetermined amount of movement of said type carrier, cushioning means interposed between said type carrier and said drive means and comprising instrumentalities to be impinged against selected stops to impart variable horizontal movement to said type carrier, and anticipator means cooperable with said stops, whereby the movement of said carrier is decelerated prior to the arrestment of said carrier by said stops.

15. In a recorder, a type carrier, said type carrier being provided with character elements divided into two main groups, each of said main groups being divided into two subgroups, permutation means responsive to received code combinations of selecting conditions for selecting a character element in each of said main groups, toggle means associated with each of said main groups, means responsive to a code combination of selecting conditions characteristic of a main group for operating the toggle means associated with said main group, permutation means in addition to said first mentioned permutation means responsive to a signaling condition accompanying each code combination for determining the selection of said character element from one or the other subgroups of the selected main group, a pair of knee-action means comprising anticipator means cooperating with said additional permutation means, means for governing the effectiveness of one of said knee-action means and simultaneously the ineffectiveness of the other of said knee-action means, and a cam bar means selectively controlled by said additional permutation means for determining which of said knee-action means is to be rendered effective, whereby type selections are effectuated in said groups according to the knee-action means rendered effective.

Certificate of Correction

Patent No. 2,505,729

April 25, 1950

WALTER J. ZENNER

It is hereby certified that errors appear in the printed specification of the above numbered patent requiring correction as follows:

Column 16, line 42, for "member 322" read *member 332*; column 18, line 6, for "How" read *Now*; column 19, line 18, for "togle" read *toggle*; column 21, line 20, for "slightly" read *slidably*; column 33, line 26, before "means", third occurrence, insert the words *parallel motion*;

and that the said Letters Patent should be read with these corrections therein that the same may conform to the record of the case in the Patent Office.

Signed and sealed this 29th day of August, A. D. 1950.
